FOCSANEANU ALEXANDER, OF NEW YORK, N. Y., ASSIGNOR TO ALLISON & HADAWAY,
A FIRM COMPOSED OF JOHN W. ALLISON AND THOMAS HADAWAY, OF NEW
YORK, N. Y.

ARC-LAMP.

1,281,745.

Specification of Letters Patent. Patented Oct. 15, 1918.

Application filed December 10, 1914. Serial No. 876,391.

To all whom it may concern:

Be it known that I, FOCSANEANU ALEXANDER, a subject of the King of Roumania, residing at New York, in the county and State of New York, have invented certain new and useful Improvements in Arc-Lamps, of which the following is a full, clear, and exact description.

The invention which forms the subject of my present application relates to arc lamps, and in the embodiments herein specifically illustrated and described it is intended particularly for photographic use, to provide the necessary illumination of the subject, either indoors or out. The chief object of the invention is to provide a portable lamp which has provision for a plurality of arcs but which is simple and durable in construction so that it may be used by inexperienced persons and subjected to hard usage without danger of being put out of order. To these and other ends the invention consists in the novel features of construction and combinations of elements hereinafter described.

In its preferred form the invention comprises two or more electrodes (or "carbons", as they are commonly termed, although they may be and often are made wholly or in part of other materials) carried by a movable plunger or piston and two or more carbons which are, by preference, carried by stationary holders. The carbons carried by the piston are in series with each other and with the stationary carbons. A suitable electromagnetic device, as for example a solenoid surrounding the plunger, is provided in series with the carbons to shift the plunger (against gravity or spring-tension) and thereby separate the movable from the stationary carbons for the production of the arcs when current, either alternating or direct, is supplied to the lamp. This provision of one automatic feeding mechanism to regulate two or more arcs in series I consider the most important feature of the invention, as it makes the apparatus simpler and more compact than is ordinarily possible in multi-arc lamps.

Convenient and effective embodiments of the invention are illustrated in the accompanying drawings, in which—

Figure 1 shows in section a complete lamp providing two arcs.

Fig. 2 is a plan view of the lamp shown

in Fig. 1, and Fig. 3 is a cross section on line 3—3.

The rod or plunger 10, Fig. 1 is movable vertically through a central aperture in the insulating head 11 of the hollow vertical cylinder 12, the lower portion of which serves as a dash pot for the piston head 13 fixed to the bottom of the plunger or piston 10. At opposite sides of the head, and fixed thereon, are two standards 14, 15, passing through openings in the plate 16 carried on the bottom of the solenoid 17 which surrounds the plunger and is itself held in place by a support 18 to which it is fastened by tie-wires 19. This support is carried by the inner ends of the terminals 20, 21, but of course is either insulated therefrom or is made of insulating material so as not to form a short-circuit across the terminals. The standards 14, 15, are provided to guide the rod 10 and prevent rotary movement thereof, as will be readily understood. The lower part of the element composed of the head 13 and the rod 10 is made of magnetic material and the upper part of non-magnetic material, so that when the solenoid is energized the said element will be drawn up. For instance, the head and the lower part of the rod (say up as far as the line 22) may be iron and the rest aluminum.

On the insulating head or closure 11 are two laterally extending brackets 23, 24, having upwardly open spring socket-pieces or carriers 25, 26 for the lower carbons 27, 28, the said pieces being threaded in the brackets to permit independent vertical adjustment of the carbons carried thereby. Set screws 29, 30 are provided to secure the socket pieces in adjusted position.

On the upper end of the rod or plunger 10 and insulated therefrom is a transverse bracket 31, in the plane of the brackets 23, 24, and provided at its ends with vertical apertures to receive the upper carbons 32, 33, which are vertically adjustable in said apertures and are held in adjusted position by set screws 34, 35.

Series-connections are provided, whereby the arcs burn in series. For this purpose the terminal 20 is connected to the end 36 of the solenoid winding, and the other end 37 of the latter is connected to the bracket 23, while the terminal 21 is connected by a wire 38 to the bracket 24.

The operation of the lamp will now be

readily understood. The carbons being in place and in contact with each other, the terminals 20, 21 are connected with the source of current, whereupon current will flow through the carbons and the solenoid in series; for example, from the source (not shown) to terminal 20, wire 36, solenoid 17, wire 37, bracket 23, carbons 27 and 32, bracket 31, carbons 33 and 28, bracket 24, wire 38, terminal 21 and thence back to the source of current. Being thus energized, the solenoid raises the plunger 10, thereby separating carbons 32 and 33 and drawing arcs between each upper carbon and the cooperating lower carbon. As the carbons are consumed the arcs lengthen, thereby cutting down the current through the solenoid and weakening the field of the solenoid. When this field becomes too weak to support its load (the carbons and other parts lifted by the solenoid) the plunger 10 descends until the increased current (due to the shortening of the arcs) gives the solenoid field sufficient strength to prevent further descent. In this way the movable carbons (in the present case the upper carbons) are fed automatically downward as they are consumed and arcs of substantially constant length are maintained.

30 When the current is cut off and the plunger allowed to descend it may be found that one or the other of the upper carbons does not come into contact with the corresponding lower carbon. On closing the circuit again it may be found that the voltage impressed is not sufficient to cause the current to jump the gap between the two separated carbons, in which case the gap can be readily closed by screwing up the socket piece (25 or 26) in its supporting bracket.

It is to be understood that the invention is not limited to the constructions herein specifically illustrated and described, but can be embodied in other forms without departure from its spirit.

What I claim is:—

1. In an arc lamp for the purpose described, in combination, a pair of stationary carbon-holders, a stem movable downwardly by gravity, a single solenoid surrounding the stem and connected in series with said stationary carbon-holders to raise said stem against gravity, and a pair of movable carbon-holders carried by the stem and fastened thereon and insulated therefrom but in electrical connection with each other, said movable carbon-holders being shifted toward the stationary carbon-holders solely by gravity and away from the same solely by the said solenoid in series with the carbon-holders.

2. In an arc lamp for the purpose described, in combination, an upright tubular shell adapted to serve as a dash pot, a piston fitted to work therein, a stem fixed to

said piston, extending upwardly through and out of said shell, and having one or more vertical guide rods, a solenoid mounted above the piston and surrounding the stem to raise the same magnetically and having a transverse baseplate at its bottom provided with one or more openings loosely fitting said guide rods to prevent rotation of the piston and stem, stationary lower carbon-holders mounted above the solenoid, carbon-holders carried by the said stem and movable therewith, and series connections for the solenoid and carbon holders.

3. In an arc lamp for the purpose described, in combination, an upright tubular shell having an insulating closure at its upper end, a piston fitted to work in said shell and having a stem extending upwardly through the insulating closure, a solenoid below the insulating closure and above the piston and surrounding the stem to raise the same magnetically, stationary lower carbon-holders mounted on said insulating closure, upper carbon-holders carried by the stem and movable therewith, a pair of terminals fitted in the side of the shell for connection with a source of current, a member fixed to the terminals and supporting the solenoid, and series-connections between the terminals and the solenoid and carbon-holders.

4. In an arc lamp for the purpose described, in combination, an upright tubular shell, a piston fitted to move vertically therein, a vertical gravity-actuated stem extending into the shell and having its inner end fixed to said piston, a carbon carrier fastened on the stem outside of said shell and having a pair of carbon-holders in electrical connection with each other but insulated from the stem, a pair of stationary carbon-holders insulated from each other, a single solenoid surrounding the stem to raise the same and having one terminal connected to one of said stationary carbon-holders, means for connecting the other terminal of the solenoid to one terminal of a source of current, and means for connecting the other stationary carbon-holder to the other terminal of the source; the lamp having but one solenoid and the carbon-holders being in series with each other and with the one solenoid.

5. In an arc lamp for the purpose described, in combination, a pair of carbon-holders insulated from each other, a pair of carbon-holders in electrical connection with each other, a gravity-actuated stem on which one of said pairs of carbon-holders is fastened to permit movement thereof, toward the other pair, only as the stem descends by gravity, a dash pot associated with the stem to oppose the gravity-motion of the stem and its carbon-holders toward the other carbon-holders; a single sole-

noid, surrounding the stem to raise the same and thereby separate the pairs of carbon-holders, and having one terminal connected to one of the insulated carbon-holders; and
5 means for connecting a source of current to the other terminal of the solenoid and to the other insulated carbon-holder, whereby current is caused to flow through the

solenoid and the four carbon-holders in series.

In testimony whereof I affix my signature in the presence of two subscribing witnesses.

FOCSANEANU ALEXANDER.
